(57) **CLAIM**

The ornamental design for a hook and hanger in combination, as shown and described.

DESCRIPTION

FIG. 1 is a front right perspective view of a hook and hanger in combination in accordance with the present invention.

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof in its environment.

The broken lines illustrating clothes hangers in FIG. 8 depict environmental subject matter that forms no part of the claimed design. The remaining broken lines depict portions of the hook and hanger in combination that form no part of the claimed design.

1 Claim, 7 Drawing Sheets
